UNITED STATES PATENT OFFICE.

WALTER P. MURPHY, OF NEW YORK, N. Y.

END STRUCTURE FOR RAILWAY CARS.

Application filed January 24, 1919. Serial No. 872,261.

To all whom it may concern:

Be it known that I, WALTER P. MURPHY, a citizen of the United States, residing at New York city, in the county of New York and State of New York, have invented certain new and useful Improvements in End Structures for Railway Cars, of which the following is a specification.

My invention relates to a corrugated steel end wall structure for railway cars, in which the strengthening and rigidifying corrugations extend vertically, or substantially so; and the primary object of the invention is to provide a car end of this type suitable more particularly for box cars, but not necessarily limited to cars of this type, having certain novel features of construction whereby the end of the car will possess great capacity to resist cargo thrusts and the strains, commonly known as "weaving" strains, to which a railway car is subjected in service.

In other words, the purpose of the invention is twofold: first, to provide against the breaking out or undue deflection of the end wall or the tearing of the end sheets from the fraying of the car due to inertia thrusts of shifting cargoes; and, second, to rigidify the car superstructure as a whole by connecting the end panels and their attachments so that the end wall will resist the tendency of the car body to become distorted or racked because of the unevenness of the track or the forces brought into play when the car rounds a curve. It might also be mentioned that not only the cargo but the entire superstructure of the car, particularly the greater portion, has a tendency to shift in the direction of the length of the car in switching, for example, or when the train stops or starts suddenly. These considerations make it of the greatest importance, if the life of the car is to be as long as possible, to so construct the end of the car body that it will not only withstand the peculiar stresses to which the end wall of a car is subjected but will also help to rigidify the superstructure of the car as a whole against the destructive forces which are constantly at work while a freight car is in service.

The invention consists in the novel and improved constructions, arrangements and combinations of parts, to be hereinafter described and claimed, for carrying out the above stated objects and such incidental objects as will appear from the following de-

scription of certain preferred embodiments of my invention.

The invention is illustrated, in two such embodiments, in the accompanying drawings wherein—

Fig. 1 is an end elevation of the superstructure and part of the under frame of a railway box car, the end of which is constructed in accordance with my invention.

Fig. 2 is a fragmentary sectional plan on line 2—2 of Fig. 1.

Fig. 3 is a fragmentary side elevation of one end of the car.

Fig. 4 is a vertical sectional view on line 4—4 of Fig. 1.

Fig. 5 is a sectional plan on line 5—5 of Fig. 1.

Fig. 6 is a sectional plan, on a larger scale, taken on line 6—6 of Fig. 1.

Fig. 7 is a fragmentary vertical section, also on an enlarged scale, taken on line 7—7 of Fig. 1.

Fig. 8 is a fragmentary end elevation of a car illustrating a modified embodiment of the invention, and

Figs. 9, 10, 11 and 12 are sectional views on lines 9—9, 10—10, 11—11 and 12—12, respectively, of Fig. 8.

Like characters of reference designate like parts in the several figures of the drawings.

Referring first to Figs. 1 to 7 inclusive, 25 indicates the end sill of a railway box car of wood construction, 26 the end plate, 27 the side sills, 28 the side plates, 29 the ridge pole and 30 the roof purlins. The side 30 sheathing of the car is shown at 31 and the flooring at 32. The end wall of the car comprises three sheet steel end panels 33, 33 and 34, the sheet 34 being preferably of heavier gauge metal than sheets 33. These sheets are formed with corrugations 35 which are preferably of the same depth from the inner surface of the sheets, are vertically disposed or substantially so, and terminate within the edges of the sheet, one 100 corrugation merging into the other so that the end wall panel as a whole has a sinuous configuration in cross section. The intermediate sheet 33 is formed with flat flanges 36 which lie back of the marginal corrugations 35 of the side sheet 33, these flanges being secured to the side sheets by lines of rivets 37 on opposite sides of these marginal corrugations. By this arrangement the end panel is given very considerable strength and rigidity.

gidity at the middle of the car where maximum strength is required, the steel itself being thicker at this place and the panel being rigidified by the box girder structures 5 35^a, 36 which form, in effect, end posts that aid in supporting the roof load as well as in checking the tendency of the end wall of the car to deflect under cargo thrusts and pressures. These posts also have a function in 10 preventing strains due to the tendency of the car to weave alluded to above. The lower edges of the end sheets are inturned to form flanges which are secured to the end sill 25 by bolts or other fastening devices 38, 15 the flange 39 of sheets 34 overlapping the flanges 40 of the side sheets 33, as best shown in Fig. 2. This arrangement provides effective means for transmitting the stresses on the vertical corrugations, and particularly 20 on the corrugations 35^a to the under frame of the car. The vertical edges of the side panels 33 are bent over to form flanges 41 which are secured by bolts 42 to the corner posts 43 of the car. Angular corner 25 gussets 44 are riveted at 45 to the lower corners of the sheets 33 and at 46 to the flanges of such sheets, these corner gussets extending down over the end sill to which they are secured by bolts 47 and over the side sills 27 30 to which they are secured by bolts 48. Similar attachments tie the end sheets to the side girders 49, 49 and to the side plates 28 of the car. The attachments to the side girders are made by means of the anchoring strips 50, 35 Similar anchoring strips 51 anchor the upper corners of flanges 42 to the side plates of the car. To the inner side of the end plate 26 is secured an angular beam 52 which extends across the car from side to side at substantially 40 the level of the upper edge of the end sheets, the bolts 53 which secure this beam in place extending through the end sheets. The upper part of the end is finished with a fascia plate 54. The beam 52 has riveted to opposite ends thereof angular gussets 55 which are secured to the side plates 28 of the car by the bolts 56 employed for fastening thereto the anchoring strips 51 above referred to. The ends of a pair of 45 crossed braces 57 are secured to the beam 52 at points, preferably approximately opposite the corrugations 35^a. The other ends of these braces are secured to angular brackets 58 attached by bolts 59 to the side plates 28 50 (Fig. 5). The braces 57 are preferably united at their place of intersection by means of a plate 60. 61 is a transverse compression member which may also serve as one of the roof carlines and which extends 55 across the car from side plate to side plate adjacent brackets 58. This member resists the tendency of the sides of the car to be drawn in through the action of braces 57 when the end structure of the car is under 60 pressure of the cargo.

I have shown the steel end structure above described as provided with a wooden lining comprising vertical strips 62 fitted into the corrugations of the end sheet and horizontally disposed lining boards 63, these parts 70 being secured together and to the end sheets by bolts 64.

The modified construction shown in Figs. 8 to 12, inclusive, is intended particularly to eliminate the wooden end plate shown in the 75 form of the invention disclosed in the preceding figures. The middle end sheet 65 is formed at its upper edge with a flange 66 and the end sheets 67 at opposite sides of the middle sheet are formed with flanges 68 80 riveted to the flange 66. The structure so formed has the slope of the roof of the car, the flanges 68 being preferably widest at the sides of the car and tapering toward the middle of the car. Flanges 68 are united 85 with the side plates 28^a by angular attaching brackets 69. This form of the invention also contemplates a pair of crossed braces here designated 57^a, 57^a which, as in the other 90 form of the invention, are attached to a transverse angular member 52^a and to brackets 58^a on the side plates 28^a, these braces being reinforced at their intersection by a plate 60^a. A plate 70 secured to the flange 66 supports a wooden filler 71 on which 95 rests the end of the ridge pole 29^a. The other parts of the car construction shown in these figures are intended to be the same as corresponding parts in the construction shown in Figs. 1 to 7 inclusive, and are 100 correspondingly indicated by reference numerals.

I claim:

1. The combination with the side walls and underframe of a railway box car, of a 105 sheet metal end structure comprising three end sheets joined together on substantially vertical lines, formed with substantially vertical corrugations and arranged so that at each place of joinder the edge of one 110 sheet extends back of and is secured at opposite sides of the marginal corrugation of the other sheet, and diagonal bracing elements extending from said end structure adjacent said marginal corrugations to the side 115 walls of the car.

2. The combination with the side walls and underframe of a railway box car, of a sheet metal end structure comprising three end sheets joined together on substantially 120 vertical lines, formed with substantially vertical corrugations and arranged so that at each place of joinder the edge of one sheet extends back of and is secured at opposite sides of the marginal corrugation of the 125 other sheet, and diagonal bracing elements which cross each other and extend from said end structure adjacent said marginal corrugations to the side walls of the car.

3. The combination with the side walls 130

and underframe of a railway box car, of a sheet metal end structure comprising three end sheets joined together on substantially vertical lines, formed with substantially vertical corrugations and arranged so that at each place of joinder the edge of one sheet extends back of and is secured at opposite sides of the marginal corrugation of the other sheet, a transverse member extending across the upper ends of said end sheets, and means for anchoring said member to the side walls of the car.

4. The combination with the side walls and underframe of a railway box car, of a sheet metal end structure comprising three end sheets joined together on substantially vertical lines, formed with substantially vertical corrugations and arranged so that at each place of joinder the edge of one sheet extends back of and is secured at opposite sides of the marginal corrugation of the other sheet, a transverse member extending across the upper ends of said end sheets, and means for anchoring said member to the side walls of the car comprising diagonal bracing elements which are attached to said member near said marginal corrugations.

5. The combination with the side walls and underframe of a railway box car, of a sheet metal end structure comprising three end sheets joined together on substantially vertical lines, formed with substantially vertical corrugations and arranged so that at each place of joinder the edge of one sheet extends back of and is secured at opposite sides of the marginal corrugation of the other sheet, a transverse member extending across the upper ends of said end sheets, and means for anchoring said member to the side walls of the car comprising diagonal bracing elements which are attached to said member near said marginal corrugations, cross each other and are secured at their opposite ends to the walls of the car.

6. The combination with the side walls and underframe of a railway box car, of a sheet metal end structure comprising three end sheets joined together on substantially vertical lines, formed with substantially vertical corrugations and arranged so that at each place of joinder the edge of one sheet extends back of and is secured at opposite sides of the marginal corrugation of the other sheet, a transverse member extending across the upper ends of said end sheets, anchoring devices for attaching the ends of said member to the side walls of the car, and diagonal braces which engage said transverse member near the middle and extend to the side walls of the car.

7. The combination with the side walls and underframe of a railway box car, of a sheet metal end structure comprising three end sheets joined together on substantially

vertical lines, formed with substantially vertical corrugations and arranged so that at each place of joinder the edge of one sheet extends back of and is secured at opposite sides of the marginal corrugation of the other sheet, a transverse member extending across the upper ends of said end sheets, anchoring devices for attaching the ends of said member to the side walls of the car, and diagonal braces which engage said transverse member near the middle, cross each other and extend to the side walls of the car.

8. The combination with the side plates of a railway box car, of a sheet metal end structure comprising three end sheets joined together on substantially vertical lines, formed with substantially vertical corrugations, and arranged so that at each place of joinder the edge of one sheet extends back of and is secured at opposite sides of the marginal corrugation of the other sheet, a transverse member on the inside of said end sheets, anchoring devices for attaching the ends of said transverse member to the side plates of the car, and diagonal braces which engage the transverse member near the middle and extend to the side plates of the car.

9. The combination with the wooden end sill, side plates and sills of a railway box car, of a sheet metal end structure comprising three end sheets joined together on substantially vertical lines, formed with substantially vertical corrugations and arranged so that at each place of joinder the edge of one sheet extends back of and is secured at opposite sides of the marginal corrugation of the other sheet, an angle bar on the inside of said end sheets anchoring devices for attaching the ends of said angle bar to the side plates of the car, crossed diagonal braces secured to the angle bar near the middle and extending and attached to the side plates, means providing an inturned substantially horizontal flange at the lower edge of said end sheets which is secured to the end sill, said end structure being formed with flanges on its vertical edges overlapping the sides of the car, and anchoring devices for attaching the upper and lower ends of said flanges to the side plates and side sills of the car.

10. The combination with the side walls and underframe of a railway box car, of a sheet metal end structure comprising three end sheets joined together on substantially vertical lines and formed with substantially vertical corrugations, and diagonal bracing elements extending from said end structure at points adjacent the place of joinder of said end sheets, crossing each other and attached to the side walls of the car.

11. The combination with the side walls and underframe of a railway box car, of a sheet metal end structure comprising a cen-

- 4
- ter sheet, side sheets of lighter material secured to said center sheet along substantially vertical lines and formed with substantially vertical corrugations, and diagonal 5 bracing elements extending from said end structure at points adjacent the place of joinder of said end sheets, crossing each other and attached to the side walls of the car.
- 10 12. The combination with the side walls and underframe of a railway box car, of a sheet metal end structure comprising three end sheets joined together on substantially vertical lines and formed with substantially 15 vertical corrugations, a rigidifying member extending across the upper ends of said sheets and anchored at its extremities to the side walls of the car, and diagonal braces connected with the end structure adjacent 20 the place of joinder of the end sheets, extending and secured to said side walls.
13. The combination with the side walls, side plates and side girths of a railway box car, of a sheet metal end structure having a 25 greater thickness of metal adjacent the vertical center of the end than at the sides of the car and formed with substantially vertical corrugations, means constituting a transverse rigidifying member adjacent the 30 upper edge of said structure, means for securing said member to the side plates of the car, and anchoring devices for securing the edges of said sheet metal structure to the side plates, side girths and side walls 35 of the car.
14. The combination with the end sill, side plates, side sills and girth members of a railway box car, of a sheet metal end structure comprising three end sheets joined together 40 along substantially vertical lines and formed with substantially vertical corrugations, the middle sheet being thicker than the side sheets and formed with flat margins extending back of the marginal corrugations of the other sheets and secured thereto on opposite 45 sides of said corrugations, said sheets being formed with inturned flanges secured to the end sill of the car, a transverse member on the inside of the end sheets, means for securing the extremities of the said transverse member to the side plates of the car, crossed diagonal braces connected with the transverse member near the middle and extending to the side plates of the car, and anchoring devices on the outside of the car for 50 anchoring said sheet metal structure to the side sills, side plates and side girths.
15. The combination with the side walls of a railway car, of a sheet metal end structure comprising three metal sheets joined together on substantially vertical lines and formed with substantially vertical corrugations, and at their upper edges with inturned flanges, which increase in width toward the sides of the car, which flanges are united together and anchored to the side walls of the car, a substantially horizontal member secured against the sheet metal structure below said flanges, and diagonal braces extending from said transverse member to the 60 side walls of the car.
16. The combination with the body of a railway car, of a sheet metal end structure comprising side sheets and a center sheet of heavier gauge than the side sheets; said 65 sheets being secured together along substantially vertical lines and formed with reinforcing corrugations, and bracing elements extending from said end structure at points adjacent said center sheet and attached to the side walls of the car.

WALTER P. MURPHY.
